LIFTING JACK

Filed May 18, 1927

UNITED STATES PATENT OFFICE

ARTHUR C. HOPKINS, OF NILES, MICHIGAN, ASSIGNOR TO NATIONAL-STANDARD COMPANY, OF NILES, MICHIGAN

LIFTING JACK

Application filed May 18, 1927. Serial No. 192,267.

The main object of this invention is to provide an improved lifting jack having a standard made up of telescoping sections which is very compact when collapsed and

5 at the same time one which has a considerable lift when fully extended.

A further object is to provide an improved lifting jack having these advantages which is easy to operate and strong and durable 10 in use.

Objects relating to details and economies of my invention will appear from the description to follow. The invention is defined in the claims.

15 A structure embodying the features of my invention is clearly illustrated in the accompanying drawings, in which:

Fig. 1 is a side view of my improved jack collapsed, the actuating screw being partially 20 broken away.

Fig. 2 is a detail view mainly in vertical central section on line 2—2 of Fig. 3.

Fig. 3 is a fragmentary view partially in section on line 3—3 of Figs. 1 and 2.

25 Fig. 4 is a fragmentary section of a modified form or embodiment of my invention.

The embodiment of the structure illustrated comprises a base 1 on which the hollow standard 2 is mounted, the standard having laterally projecting ears 3 at its lower end secured to the standard by means of the rivets 4. At its upper end the standard has an inturned flange 5.

The base is provided with an arm-like extension 6 having a way therein comprising a central cylindrical bore-like portion 7 and opposed groove-like or channel portions 8 opening to the central section 7. This way is curved at its inner end and opens upwardly

35 to the lower end of the standard. The standard has groove-like ways 9 therein registering with the ways or channels 8 of the base and its arm extension.

The lifting member is made up of a tubular outer or bottom section 10 and a top or inner section 11 telescoping within the bottom section, the top section having a head 12. The bore 13 of the outer or bottom lifting member section corresponds in diameter to the bore-like portion 7 of the way in the base so that

when the lifting member is collapsed the bore 13 of the outer lifting member section registers with the bore-like portion 7 of the guide-way.

The actuating screw 14 is adapted to telescope or project into the arm 6 and is provided with a nut 15 removably engageable with the arm. The nut has a sleeve portion 16 embracing the end of the arm and provided with bayonet slots 17 coacting with the pins 18 on the arm. The advantage of this is compactness when disassembled and convenience in assembling.

The power is transmitted from the screw to the lifting member by means of a series 65 of spherical thrust members 20 and a series of elongated thrust members 21, these members being in the preferred embodiment of a general H-shape. The thrust members 20 are adapted to travel in the way or bore 7 and to 70 enter the lifting member section 10 when it is collapsed within the standard. The thrust members 21 extend across the bore 7 engaging and traveling in the grooves 8. This H-shape permits the thrust members 21 to 75 swing around the groove at the inner end of the bore 7.

A bearing ball 22 is preferably disposed between the inner end of the screw and the adjacent thrust member 21. The outer end 80 of the arm is spun in at 23 to retain the thrust members when the screw is removed.

In the modification shown in Fig. 4 cylindrical thrust members 24 are substituted for the thrust members 21, these thrust members 85 24 being connected by cables 25 arranged through the ends thereof to prevent their getting out of parallel relation or becoming wedged in the ways.

With the parts thus arranged the power 90 from the screw is effectively transmitted to the lifting member, there being, in effect, a flexible power transmitting means. These thrust members are arranged so that they are maintained in alinement and cannot become wedged or locked.

I have illustrated and described my invention in an embodiment which I regard as very practical. I have not attempted to illustrate or describe other adaptations or modifi- 100

cations as it is believed this disclosure will enable those skilled in the art to embody or adapt the same as may be desired.

Having thus described my invention what I claim as new and desire to secure by Letters Patent is:

1. In a lifting jack, the combination with a standard having a longitudinal bore therein and provided with a base having a laterally projecting arm, said base and arm having a bore therein upwardly curved at its inner end and opening to the bore of said standard, said base, arm and standard having opposed longitudinal groove-like guide ways therein opening to their said bores, a lifting member comprising inner and outer telescoping sections, the outer section having telescoping engagement with said standard, the bore of the outer section opening to the bore of said standard and corresponding in diameter to that of said base and arm, an actuating screw, a coacting nut removably engageable with the outer end of said arm, a plurality of H-shaped thrust members disposed with their ends in said guide ways, a thrust ball disposed between the inner end of said screw and the said thrust members, and a plurality of thrust balls disposed to travel in said bores between the said H-shaped thrust members and said inner lifting member section and coacting with the lower end thereof, said balls being adapted to enter the outer lifting member section as the inner section is projected therefrom.
2. In a lifting jack, the combination with a standard having a longitudinal bore therein and provided with a base having a laterally projecting arm, said base and arm having a bore therein upwardly curved at its inner end and opening to the bore of said standard, said base, arm and standard having opposed longitudinal groove-like guide ways therein opening to their said bores, a lifting member comprising inner and outer telescoping sections, the outer section having telescoping engagement with said standard, the bore of the outer section opening to the bore of said standard and corresponding in diameter to that of said base and arm, a series of thrust members disposed with their ends in said guide ways, a series of thrust balls disposed to travel in said bores between the said first mentioned series of thrust members and said inner lifting member section and coacting with the lower end thereof, said balls being adapted to enter the outer lifting member section as the inner section is projected therefrom, and an actuating screw projecting into said arm.
3. In a lifting jack, the combination with a standard having a longitudinal bore therein and provided with a base having a laterally projecting arm, said base and arm having a bore therein upwardly curved at its inner end and opening to the bore of said standard, said base, arm and standard having opposed longitudinal groove-like guide ways therein opening to their said bores, a lifting member comprising inner and outer telescoping sections, the outer section having telescoping engagement with said standard, the bore of the outer section opening to the bore of said standard and corresponding in diameter to that of said base and arm, an actuating screw, a coacting nut removably engageable with the outer end of said arm, a plurality of thrust members disposed with their ends in said guide ways, and a plurality of thrust balls disposed to travel in said bores between the said first mentioned thrust members and said inner lifting member section and coacting with the lower end thereof, said balls being adapted to enter the outer lifting member section as the inner section is projected therefrom.
4. In a lifting jack, the combination with a standard having a longitudinal bore therein and provided with a base having a laterally projecting arm, said base and arm having a bore therein upwardly curved at its inner end and opening to the bore of said standard, said base, arm and standard having opposed longitudinal groove-like guide ways therein opening to their said bores, a lifting member comprising inner and outer telescoping sections, the outer section having telescoping engagement with said standard, the bore of the outer section opening to the bore of said standard and corresponding in diameter to that of said base and arm, a series of thrust members disposed with their ends in said guide ways, a series of thrust balls disposed to travel in said bores between the said first mentioned series of thrust members and said inner lifting member section and coacting with the lower end thereof, said balls being adapted to enter the outer lifting member section as the inner section is projected therefrom, and an actuating screw projecting into said arm.
5. In a lifting jack, the combination with a standard provided with a base, a lifting member comprising sections telescopingly associated with each other and with said standard, said base, standard and outer section of said lifting member being provided with communicating ways of cylindrical cross section, the ways of the outer section of the lifting member and base being of corresponding diameter and being positioned end to end when the outer section is collapsed within the standard, the base and standard having opposed channel guide ways therein opening to their said cylindrical guide ways, an actuating screw mounted on said base to be projected into and retracted from its said guide way, a series of spherical thrust members traveling in and guided by said cylindrical guide ways and adapted to enter the said outer lifting member section to coact with the inner lifting member section, and a plu-

said base, arm and standard having opposed longitudinal groove-like guideways therein opening to their said bores, a lifting member comprising inner and outer telescoping sections, the outer section having telescoping engagement with said standard, the bore of the outer section opening to the bore of said standard and corresponding in diameter to that of said base and arm, a series of H-shaped thrust members disposed with their ends in said guide ways, a series of thrust balls disposed to travel in said bores between the said H-shaped thrust members and said inner lifting member section and coacting with the lower end thereof, said balls being adapted to enter the outer lifting member section as the inner section is projected therefrom, and an actuating screw for projecting into said arm.

4. In a lifting jack, the combination with a standard having a longitudinal bore therein and provided with a base having a laterally projecting arm, said base and arm having a bore therein upwardly curved at its inner end and opening to the bore of said standard, said base, arm and standard having opposed longitudinal groove-like guide ways therein opening to their said bores, a lifting member comprising inner and outer telescoping sections, the outer section having telescoping engagement with said standard, the bore of the outer section opening to the bore of said standard and corresponding in diameter to that of said base and arm, a series of thrust members disposed with their ends in said guide ways, a series of thrust balls disposed to travel in said bores between the said first mentioned series of thrust members and said inner lifting member section and coacting with the lower end thereof, said balls being adapted to enter the outer lifting member section as the inner section is projected therefrom, and an actuating screw projecting into said arm.

5. In a lifting jack, the combination with a standard provided with a base, a lifting member comprising sections telescopingly associated with each other and with said standard, said base, standard and outer section of said lifting member being provided with communicating ways of cylindrical cross section, the ways of the outer section of the lifting member and base being of corresponding diameter and being positioned end to end when the outer section is collapsed within the standard, the base and standard having opposed channel guide ways therein opening to their said cylindrical guide ways, an actuating screw mounted on said base to be projected into and retracted from its said guide way, a series of spherical thrust members traveling in and guided by said cylindrical guide ways and adapted to enter the said outer lifting member section to coact with the inner lifting member section, and a plu-

rality of elongated thrust members extending across said cylindrical guide way into said channel guide ways and interposed between said spherical thrust members and said actuating member.

- 5 6. In a lifting jack, the combination of a standard provided with a base, a lifting member comprising telescoping sections telescopingly associated with said standard, said base and standard having communicating ways comprising a central portion and channel side portions opening thereto, a series of thrust members traveling in the central portion of said ways and adapted to enter the 10 outer lifting member section when the outer section is collapsed within the standard, a second series of thrust members adapted to travel in and supported by the channel side portion of said guideway, and an actuating 15 screw coacting with the second series of thrust members.

- 20 7. In a lifting jack, the combination of a standard provided with a base, a lifting member comprising sections telescopingly associated with each other and with said standard, said base and standard being provided with a way having opposed channel-like side portions and an enlarged central portion, a series of thrust members traveling in and 25 guided by said central portion of said way and adapted to enter the outer lifting member section to coact with the inner lifting member section, a series of elongated thrust members traveling in said channel-like portions of said ways, and an actuating means coacting with said thrust members.

- 30 8. In a lifting jack, the combination with a standard, a lifting member comprising sections telescopingly associated with each other and with said standard, a series of spherical thrust members adapted to enter the outer lifting member section to coact with the inner section, said standard being provided with opposed channel-like thrust member 35 guide ways, thrust members traveling in said guide ways to coact with said spherical thrust members, an actuating screw, and a guide way into which said thrust members may retract when the lifting member is collapsed.

- 40 9. In a lifting jack, the combination of a standard, a lifting member comprising sections telescopingly associated with each other and with said standard, said standard being provided with opposed groove-like ways, a series of thrust members adapted to enter the outer lifting member section to engage the inner lifting member section when the outer section is in collapsed position within 45 said standard, a second series of thrust members traveling in said ways to project said outer lifting member from said standard, and an actuating screw coacting with said thrust members.

- 45 10. In a lifting jack, the combination of a

standard, a lifting member comprising sections telescopingly associated with each other and with said standard, said standard being provided with opposed groove-like ways, a series of thrust members adapted to 50 enter the outer lifting member section to engage the inner lifting member section when the outer section is in collapsed position within said standard, a second series of thrust members traveling in said ways to 55 project said outer lifting member from said standard, and an actuating means coacting with said thrust members.

60 11. A standard, a lifting member in the standard and comprising two telescoping parts, a series of thrust members adapted to enter one of the said telescoping parts to extend the other therefrom, a second series of thrust members in line with the first series and adapted to enter the standard to project 65 the lifting member therefrom, means for holding said second series of thrust members in alignment in the standard, and actuating means for moving said thrust members to extend the lifting member and project the same 70 from the standard.

75 12. A standard, a lifting member in the standard and comprising two telescoping parts, a series of thrust members adapted to enter one of the said telescoping parts to 80 extend the other therefrom, a second series of thrust members in line with the first series and adapted to enter the standard to project the lifting member therefrom, means for holding said second series of thrust members in alignment in the standard including 85 guides in the standard and cooperating parts on the thrust members engaging such guides, and actuating means for moving said thrust members to extend the lifting member and project the same 90 from the standard.

95 13. A standard, a lifting member in the standard and comprising two telescoping parts, a series of thrust members adapted to enter one of the said telescoping parts to extend the other therefrom, a second series of thrust members in line with the first series and adapted to enter the standard to project the lifting member therefrom, means for holding said second series of thrust members in alignment in the standard, and actuating means for moving said thrust members to extend the lifting member and project the same from the standard including 100 a case and a screw therein adapted to be urged against the end of the thrust members, the case being adapted to receive the thrust members when the screw is retracted.

105 14. A standard, a lifting member in the standard and comprising two telescoping parts, a series of thrust members adapted to enter one of the said telescoping parts to extend the other therefrom, a second series of thrust members in line with the first series and adapted to enter the standard to project 110

the lifting member therefrom, means for holding said second series of thrust members in alignment in the standard, actuating means for moving said thrust members to extend the lifting member and project the same from the standard including a case and a screw therein adapted to be urged against the end of the thrust members, the case being adapted to receive the thrust members when the screw is retracted, and means to hold the thrust members in alignment in the case.

15. A lifting jack comprising a standard having a bore, a thrust member receiving extension having a bore communicating with the lower end of the bore of the standard, a series of thrust members in said extension, means for forcing said thrust members from said extension into the bore of the standard, a lifting member comprising telescoping sections telescoping in the bore of the standard and adapted to be elevated by said thrust members, and means within said standard with which a plurality of said thrust members may engage for retaining said thrust members in vertical alignment within the standard for elevating said lifting member, the outer lifting member being adapted to receive a series of thrust members projected and supported by the series engaged in said aligning means.

30. 16. A jack comprising a standard having a bore, a thrust member receiving extension having a bore communicating with the lower end of the bore of the standard, a series of thrust members lying in said extension, means for forcing said thrust members from said extension into the bore of the standard, a lifting member comprising telescoping sections telescoping in the bore of the standard, and means within the standard with which a plurality of thrust members coact for aligning them within the standard for projecting the lifting member, the outer lifting member being adapted to receive a second series of thrust members projected by the first whereby the inner lifting member is projected from the outer.

In witness whereof I have hereunto set my hand.

50 ARTHUR C. HOPKINS.
